CIRCUIT BREAKER

Kurt Wulsten, Berlin-Charlottenburg, Germany,
assignor to Westinghouse Electric & Manufacturing Company, East Pittsburgh, Pa., a corporation of Pennsylvania

Application February 21, 1934, Serial No. 712,344
In Germany February 25, 1933

34 Claims. (Cl. 175—294)

My invention relates particularly to circuit breakers of the type used for controlling lighting and moderate power distribution or network circuits.

5 Circuit breakers for this type of service present a rather complex problem to the electrical art. Ordinarily, they are used in homes or factories and must, therefore, be positive in operation and absolutely safe. Preferably the breakers are 10 quick-make and quick-break to prevent circuit disturbances or prolonged arcing; the trip devices used with the breakers must be reliable and accurate in operation and must cause the opening of the controlled circuit irrespective of the 15 position of the operating member; and in addition the operating mechanism and the trip device should be entirely resettable after each opening of the circuit as a result of the operation of the trip device by movement of the operating 20 member. As against these operational requirements, a commercially successful breaker must be 25 low in cost, due to the large number used in even a moderately sized building or factory, and due to the fact that the devices compete directly with the older fuse and separate switch combination.

The principal object of my invention is, therefore, the provision of an improved circuit breaker of the above described type that shall satisfactorily meet all present day operational requirements, and that shall at the same time be low in cost.

This object of my invention is accomplished through the provision of an improved operating mechanism for actuating the circuit breaker contacts and through the provision of an improved trip device which cooperates with the mechanism to secure the desired operation of the circuit breaker.

The operating mechanism of my invention utilizes 40 a pair of toggle links and a manually movable operating member for moving the contacts to the open and to the closed-circuit position. In contrast to the usual arrangement of toggle operating linkages, the line of action of the toggle is nearly straight when the breaker is open and is substantially bent when the breaker is closed. This arrangement necessitates the application of a large force to the operating member in order to initiate movement of the contacts toward the closed-circuit position. And, since the component of force which causes the movement of the contact members toward the closed circuit position progressively increases (due to the bending of the toggle) as the closing operation progresses, the contacts are effectively

closed at high speed without the use of an over-center spring. Moreover, since the toggle linkage is bent when the breaker is in the closed circuit position, it is possible to secure a much more rapid opening of the circuit breaker contacts 5 than has been heretofore possible, due to the fact that it is not necessary to move the knee of the toggle through the overcenter or extended position when effecting the opening of the breaker.

To support the toggle linkage so that the operation of the trip device shall cause the automatic opening of the circuit breaker, irrespective of the position of the operating member, I provide a second toggle linkage, which in the preferred form comprises a pair of pivotally joined link members. This supporting linkage is disposed intermediate the operating linkage and the trip device and is adapted to be substantially straight when the breaker is in the closed circuit position in order to minimize the forces which must be balanced by the trip device.

In the improved trip device which is utilized in this embodiment of my invention, I provide a single trip bar which is actuatable by any one of a plurality of electroresponsive tripping elements. 25 In order to meet the increasingly severe requirements of the type of service for which these breakers are intended, I provide one or more electro-magnetic tripping elements and one thermally responsive tripping element, each of which is energized in response to the current flowing through one of the poles of the breaker. Each of the tripping elements is individually capable of causing the operation of the trip device on the occurrence of predetermined overload conditions 35 which are different from the predetermined overload conditions which cause the operation of the other devices. It is thus possible to secure protection over any range of requirements which might be encountered in ordinary service. All of the 40 several tripping elements directly engage, or are in part supported upon, the single trip bar, and by virtue of this arrangement a substantial reduction in the cost of the apparatus is effected.

The novel features of my invention and the preferred method of embodying those features into a commercial type circuit breaker will be made more apparent by reference to the following description and drawings, wherein—

Figure 1 is an elevational view, partially in section, of a two-pole circuit breaker embodying the principal features of my invention.

Fig. 2 is a front elevational view of the circuit breaker shown in Figure 1. The cover has been 55

removed in order to more clearly illustrate the structure features involved.

Fig. 12 is a fragmentary view, partially in section, showing the features of the combined blow-out and trip coils, and

Fig. 13 is a fragmentary view, partially in section, on the line XIII-XIII of Fig. 12.

The circuit breaker shown in the drawings comprises generally a base 1 of molded insulating material upon which are mounted a pair of terminal contacts 3 and 5 for connection with the line side of the supply circuit, a pair of stationary contact members 7, a pair of movable contact members 9 for cooperating therewith to open and close the circuit, a toggle link operating mechanism 11 for moving the breaker to the open and the closed circuit position, a pair of blow-out coils 13 for moving the arc established incident to the opening of the controlled circuit into suitable arc chutes 15, a trip device 17 which includes a plurality of magnetically responsive tripping elements and a plurality of thermally responsive tripping elements, and a second pair of terminals 19 and 21 for connecting the breaker to the load side of the circuit. A suitable cover 23, also of molded insulating material, is provided for enclosing the moving parts of the breaker.

The stationary contacts 7 are each formed from a suitably bent strip of conducting material which is rigidly supported on the base 1 by means such as a screw fastening or the like. The movable contact members 9 are each supported upon the base 1 through the agency of a resilient support member 25. One end of each of these support members 25 is electrically and mechanically connected to the associated contact member 9 by means of a screw 27, to permit easy replacement of the moving contact members, and the other end is supported upon the base 1 and is at the same time connected to the terminal 29 of one of the blow-out coils 13 by a screw fastening 31.

Each of the blow-out coils 13 is wound in the usual manner about a core member 33 which is shown particularly in Figs. 12 and 13. Each of these core members 33 is provided with two pairs of pole pieces 35 and 37. The upper pair of pole

pieces 35 is used for supporting the arc chutes 15 and for providing the magnetic field which moves the arc within the chutes, and the lower pair of pole pieces 37 is used, as will be described in some detail later, for attracting one of the armatures 52 supported upon the trip bar 50 to effect the operation of the trip device 17.

The lower terminal 39 of each of the blow-out coils 13 is connected by means of a bolt 41 to the terminal 43 of one of the energizing coils 45 for the magnetically responsive tripping device shown particularly in Figure 6. The other terminal 47 of each of the energizing coils 45 is connected by suitable means to the terminal 49 of one of the bimetallic thermally responsive tripping elements 51, shown particularly in Fig. 7. The other terminal 53 of each of the bimetallic tripping elements 51 is connected to one of the load terminals of the breaker by means of a strip of conducting material 55 and suitable screw fastenings 57.

The electrical circuit for each of the poles is thus seen to be comparatively direct. Beginning with the line terminal 5, the current flows progressively through the stationary contact 7, the moving contact 9, the supporting strip 25 therefor, the blow-out coil 13 and thence the energizing coil 45 for the electromagnetic tripping element, and the U-shaped bimetallic member 51, to the line terminal 21.

The operating mechanism 11 for moving the contacts 9 to the open and to the closed-circuit position is entirely supported upon a U-shaped frame member 59 which is rigidly affixed to the base 1. It includes an operating member 61 having a knob 63 of insulating material which is adapted to cooperate with a suitable guide opening 65 in one portion of the mechanism frame, and a guide pin 67 which cooperates with a second suitably proportioned opening 69 for defining the path of movement of the operating member. Both of the moving contact members 9 are biased to the open circuit position at all times by virtue of the resiliency of their support members 25, and in order to actuate the breaker contacts, a pivotally supported insulating member 71 is provided. This member has three projections 73, 75 and 77 formed integrally therewith. Two of these (73 and 75) serve to engage the flexible supports 25 for the moving contacts 9 to permit normal operation of the breaker, and the third (77) serves as one of the links of the toggle operating mechanism. The other link of the toggle operating linkage comprises a flat link member 79 pivotally joined at one end to the projection 71 and pivotally joined at the other end to the upper link 81 of the toggle support linkage.

The operating member 61 engages the operating toggle linkage through a slot 83 which is adapted to slidably engage the pivot pin 85 which joins the operating and support linkages. By virtue of this slot and pin connection, it is possible for the trip device 17 to cause the opening of the breaker irrespective of the position of the operating member.

The toggle support linkage comprises the upper link 81, previously mentioned, and a second link member 87 formed in the shape of a bell crank lever. The apex of this bell crank lever 87 is pivotally joined to the upper toggle link 81 by the knee pivot pin 89, and one of the side portions is pivotally supported on a pin 91 which projects outwardly from the frame 59 of the operating mechanism. The end 93 of the other side portion of the bell crank link 87 is

adapted to engage a suitable latching member 95 forming a part of the trip bar 50.

In order to facilitate the opening of the breaker, a spring 97 is provided for biasing the operating member 61 to the open circuit position. This spring 97 also serves the function of automatically restoring the several parts of the breaker and the trip device to an operative position following an opening of the breaker resulting from the operation of the trip device. The force exerted by the spring 97 is incapable of opening the breaker under normal operating conditions.

The trip device 17 comprises, as mentioned above, a single, pivotally supported trip bar 50, having a latch member 95 at one end thereof for cooperating with the support toggle linkage to permit manual operation of the breaker, and a plurality of tripping elements for causing the breaker to open automatically upon the occurrence of predetermined conditions in the controlled circuit. A U-shaped saddle member 99 is supported upon the central portion of the trip bar 50 and is rigidly affixed thereto, as is shown in Fig. 7. Affixed to the base portion of this saddle are a pair of rigid metal strips 101 each of which serves to support one of the iron armatures 52, at its upper end. The armatures 52 are positioned, in the assembled breaker, adjacent the pole pieces 37 which are energized by the combination blow-out and trip coils 13, and are each individually biased out of engagement with those pole pieces 37 by means of suitable coil springs 103 retained within recesses 105 formed in the base 1. In addition to the magnetically responsive tripping elements formed by the armatures 52, and the energizing means therefor, the trip device includes a second electromagnetically responsive tripping means which includes a separate electromagnetically responsive tripping element for each of the two poles of the breaker.

This second tripping means is shown particularly in Fig. 6 and is normally energized by either of the coils 45, each of which is connected in series with the circuit controlled by one of the pairs of separable contacts. Either of the two coils 45 is capable of attracting an armature 107, upon the occurrence of predetermined overload conditions, to cause the operation of the trip device. The tripping coils 45 are supported upon a portion of the frame 59 utilized for supporting the operating mechanism, and are each adapted to energize a suitable core member 109 which cooperates with the movable armature 107. The armature 107 is formed from a tubular means of magnetic material and is open at the lower end.

During the normal operation of the device, the armature 107 moves within a guide tube 111 of insulating material disposed within the attracting coils 45. This tube 111 is provided with a slot 113 within which a projection 115 formed integral with the armature moves to cause rotation of the trip bar 50 during the tripping operation. A screw 117 is provided for controlling the distance separating the armature 107 and the core 109 of the attracting means therefore, in order to permit adjustment of the tripping point.

The trip bar 50 is provided with an L-shaped arm 119 rigidly affixed thereto at its midpoint. The upper end 121 of this arm is adapted to engage the projection 115 on the armature 107 of the magnetically responsive tripping means, and

the other end is provided with a member 123 adapted to be engaged by the movable end 124 of each of the thermally responsive tripping elements 51.

It will thus be seen that the trip device is provided with three electro-responsive tripping elements for each of the two poles of the breaker. By a proper selection of the number of turns in the blow-out coils 13 and the number of turns in the coils 45 used for energizing the other magnetically responsive tripping means, it is possible to secure protection of the controlled apparatus over a wide range of current value. All of the magnetically responsive tripping elements are individually operable to cause the opening of the breaker immediately following the occurrence of predetermined conditions. Each of the thermally responsive tripping elements 51, however, is operable to cause the actuation of the trip device only after a time delay which is inversely proportional to the current flowing therethrough.

The operating mechanism and the contacts of the circuit breaker are shown in the normal open-circuit position in Fig. 3. To close the contacts manually, a force is applied to the operating member in the direction toward the base. By virtue of the fact that the knee pivot pin 125 of the operating toggle is only a short distance from the center line of the toggle (the line connecting the pin 85 and the pivotal support for the contact actuating member 11) only a very small component of this force is effective to cause movement of the contacts from the open-circuit to the closed-circuit position. Thus, in order to close the breaker, it is necessary to apply a very considerable force to the operating member 61. However, as soon as movement is initiated, the effective component of the motion producing force increases at a very rapid rate, and since it is substantially impossible to prevent the hand from following the operating member at least a short distance, the contacts are closed with what is substantially a snap action. The moving parts of the operating mechanism then take the position shown in Fig. 4.

During the circuit-closing operation, the support linkage moves from the bent position shown in Fig. 3 to a substantially straight position as shown in Fig. 4. The support linkage is thus able to balance the large reaction force which may be transmitted through the operating mechanism by a very small force. This arrangement reduces to minimum the force which must be supplied by the tripping device 17 and thereby permits the securing of a maximum of sensitivity in that device. When in the closed-circuit position, the support linkage is always in the over-center position, thereby assuring that the release of the end 93 of the bell crank lever 87 by the trip device 17 will positively effect the opening of the breaker.

Upon the occurrence of an overload in the circuit controlled by either of the poles of the breaker which is of sufficient magnitude and duration to cause the actuation of any one of the three tripping elements, the trip bar 50 is rotated, in a clockwise direction. This rotation causes the eccentrically mounted latching member 95 to disengage the end 93 of the bell crank lever 87 and in so doing causes the support linkage to become incapable of holding the operating linkage in the closed circuit position. The moving parts of the breaker then move automatically to the position shown in Fig. 5, the slot and pin 75

connection intermediate the operating member and the operating handle making it possible for the trip device to cause the automatic opening of the breaker irrespective of the position of that member. Moreover, since the operating linkage is bent very considerably when the breaker is in the closed circuit position, any movement of that linkage which may be produced by a release of its supporting means serves to cause the opening 10 of the breaker contacts at the maximum possible speed.

The contacts may be opened manually by pulling the operating member 61 away from the base. This method of operation is not desirable, however, because of the fact that it has a tendency to cause delayed opening of the contacts. To prevent such delayed opening, I provide a slidable member 127 having an insulating button 129 which projects through the cover 23 of the circuit breaker for directly engaging the trip bar 50 to cause the rotation of that member, and thereby effect the opening of the breaker exactly as described above. The body portion of the slidable member 127 engages a suitable guide opening 131 in the frame 59 and is positioned thereon through the engagement of a slotted opening 133 with the pin 91. The right-hand end (Fig. 1) of the member 127 has suitable means for engaging the trip bar 50 to cause it to 36 rotate to the tripped position.

As soon as the contacts have moved to the open-circuit position following the actuation of the trip device 17, the spring 97 moves the operating member 61 to the normal open-circuit position and in effecting this movement causes the support linkage to be moved from the position shown in Fig. 5 to the position shown in Fig. 3. The opening of the circuit effects the removal of the overload condition from the breaker, and the trip bar 50 is then free to move under the action of the biasing springs 103 to the untripped position, in which position the end 93 of the bell crank lever 27 reengages the latching member 95 so as to permit the supporting linkage to hold the operating linkage in the closed circuit position.

For certain applications it is desirable that the circuit breaker shall open the circuit immediately upon the occurrence of a breakdown of the insulation within the controlled equipment. With the breaker of my invention it is very simple to include protection against this condition merely through the provision of an extra tripping coil and a simple switching equipment. The electrical connections for a circuit of this type are shown in Fig. 9 wherein the numerals 3, 5, 19 and 21 represent the terminals of the breaker, and the numerals 7 and 9 represent the separable contacts. Essentially, this device comprises nothing more than an extra coil 135 (Fig. 6) adapted to attract the armature 107 forming a part of the previously described magnetically responsive tripping means, a means which includes the terminals 137 and 139 for connecting that coil into an electrical circuit, and a switching means 141 (shown particularly in Fig. 11) for permitting the testing of the coil.

The terminal 145 of the coil 135 is directly connected to the breaker terminal 137, and the other terminal 147 of the coil is connected to a double arm lever 149 which is supported on a pin 151. One arm of the lever 149 is provided with a lateral lug 153 which engages the terminal member 139 while the other arm of the lever carries a contact plate 155. Thus when the breaker is

in the normal open circuit position, the coil 135 is directly connected to the terminals 137 and 139. A resistance rod 157 of a carbonaceous or like material is positioned within a suitable guide clamp 159 affixed to the base 1 so that it may be 5 slidably moved and is used as a testing resistance. The end 160 of this rod 157 which is normally disposed a short distance away from the plate 158 is tipped with metal, and the other end is provided with an annular metal member 161 normally pressed against the contact member 162 which is electrically connected to the terminal 19, the rod 157 being held in this position by a biasing spring 163.

A member 165 which is slidably supported on 15 the frame 59 is provided for actuating the switching lever 149. If pressure is exerted on the insulating knob 167 affixed to the upper portion of this member 165 the lug portion 153 (Fig. 10) of the double arm lever 149 will be caused to disengage the terminal 139. The plate portion 155 of the lever 149 will then engage the end 160 of the resistance rod 157, thereby connecting one end of the coil 135 to the circuit controlled by one of the poles of the breaker, the resistance element 157 being in series with the coil. Further pressure on the insulating knob 167 will cause the lever 149 to effect the disengagement of the annular member 161 from the contact member 162 connected to the terminal 19, and subsequently 30 will cause the annular member 161 to engage the conducting member 168 normally electrically connected to the terminal 21 of the breaker.

In the circuit shown in Fig. 9, the terminal 139 of the special tripping device is normally connected to the ungrounded frame of a piece of electrical equipment as indicated at M. The other terminal 137 of the testing device is grounded at G.

Upon the breakdown of the insulation between 40 the frame of the device M and the current carrying conductors thereof, a current will be caused to flow through the coil 135 which is capable of causing the operation of the trip device 17, thereby opening the breaker. The selective means 45 for connecting the coil 135 in series with either pole of the breaker is provided for testing the device to show that the fault tripping apparatus is in an operative condition and that the electrical circuit is intact. It is necessary that it be possible to connect the coil 135 to either of the two poles of the breaker, because the breaker may be used on a direct-current circuit having one side thereof grounded. On an alternating-current circuit having a grounded neutral it is of course 55 necessary to connect the coil to only one of the two phases in order to test the device.

From the foregoing, it will be seen that I have provided an improved circuit interrupter which utilizes an extremely simple form of operating 60 mechanism and trip device. The operating mechanism of my improved breaker is capable of opening and closing the circuits at high speed without requiring the use of an over-center operating spring, and the trip device is capable of 65 causing the opening of the breaker irrespective of the position of the operating member. The improved operation of the device results, at least in part, from the novel form and arrangement of the operating and support linkages, and the arrangement of these linkages is believed to be an 70 important feature of my invention.

The trip device which, in conjunction with the improved operating mechanism disclosed, accomplishes the objects of my invention, is much sim- 75

pler than the devices heretofore known in the art. It comprises a single pivotally supported trip bar which is operable by any of a plurality of electro-responsive elements. In addition to the 5 fact that my improved trip device utilizes merely a single trip bar that bar is employed for supporting the armature of at least one of the electro-responsive tripping elements.

Another novel feature of my invention is the 10 provision of means for causing the opening of the breaker upon a failure of the insulation in an ungrounded piece of electrical equipment and the combination with that means of means for testing the operation thereof.

15 In addition to the above features which are capable of wide adaptations to circuit breakers generally, I have disclosed certain structural details which are of particular value in carrying out the objects of my invention as pointed out in the 20 appended claims.

While in accordance with the patent statutes I have disclosed the foregoing details of a preferred embodiment of my invention, it is to be understood that many of these details are merely 25 illustrative and that variations in their precise form will be both desirable and necessary in certain applications. I desire, therefore, that the language of the accompanying claims shall be accorded the broadest construction and that my 30 invention shall be limited only by what is expressly stated therein and by the prior art.

I claim as my invention:

1. In a circuit interrupter, separable contact means for opening and for closing the circuit, 35 actuating means for moving said contact members to the open and to the closed circuit position, and a trip device operable upon the occurrence of predetermined conditions to cause said actuating means to automatically move said contact means 40 to the open circuit position, said actuating means including a toggle linkage for operatively engaging said contact means, and a second toggle linkage intermediate said first toggle linkage and said trip device for supporting said first toggle 45 linkage, said first toggle linkage being substantially straight when said interrupter is in the open circuit position and being bent at the knee thereof when said interrupter is in the closed circuit position to facilitate rapid opening of the controlled circuit, said second toggle linkage being substantially straight when said interrupter is in the 50 closed-circuit position.

2. In a circuit interrupter, separable contact means for opening and for closing the circuit, 55 actuating means including an operating member for moving said contact members to the open and to the closed-circuit position, and a trip device operable upon the occurrence of predetermined conditions to cause said actuating means to automatically move said contact means to the open-circuit position, said actuating means including a toggle linkage intermediate said operating member and said contact means, and a support for 60 said toggle linkage which comprises a second toggle linkage, one end of which operatively engages said trip device, said first toggle linkage being substantially straight when said interrupter is in the open-circuit position and being bent at the knee thereof when said interrupter is in the closed-circuit position to facilitate rapid opening of the controlled circuit upon the actuation of 65 said trip device, said second toggle linkage being substantially straight when said interrupter is in the closed-circuit position in order to minimize 70 the tripping force which must be supplied by 75

said trip device, said second toggle linkage collapsing upon the actuation of said trip device and thereby becoming incapable of holding said first linkage in the closed-circuit position.

3. In a circuit interrupter, separable contact 5 means for opening and for closing the circuit, actuating means including an operating member for moving said contact members to the open and to the closed-circuit position, and a trip device operable upon the occurrence of predetermined 10 conditions to cause said actuating means to automatically move said contact means to the open-circuit position, said actuating means including a toggle linkage intermediate said operating member and said contact means, and a support for 15 said toggle linkage which comprises a second toggle linkage one end of which operatively engages said trip device, said first toggle linkage being substantially straight when said interrupter is in the open-circuit position and being bent at 20 the knee thereof when said interrupter is in the closed-circuit position to facilitate rapid opening of the controlled circuit upon the actuation of said trip device, said second toggle linkage being substantially straight when said interrupter is in 25 the closed-circuit position in order to minimize the tripping force which must be supplied by said trip device, said second toggle linkage collapsing upon the actuation of said trip device and thereby becoming incapable of holding said first link- 30 age in the closed-circuit position irrespective of the position of said operating member.

4. In a circuit interrupter, separable contact means for opening and for closing the circuit, 35 actuating means including an operating member for moving said contact members to the open and to the closed-circuit position, and a trip device operable upon the occurrence of predetermined conditions to cause said actuating means to automatically move said contact means to the open-circuit position, said actuating means including 40 two pairs of toggle links, one of the said two pairs of toggle links being substantially straight when said interrupter is in the open-circuit position to facilitate rapid closing of the contact means during the circuit-closing operation, the other of the said two pairs of toggle links serving as a support for the first pair of toggle links in order to permit normal operation of said interrupter in response to movement of said operating members, said 45 second pair of toggle links being normally restrained in a position where it supports said first pair of toggle links in an operative position by means associated with said trip device.

5. In a circuit interrupter, separable contact 55 means for opening and for closing the circuit, actuating means including an operating member for moving said contact members to the open and to the closed-circuit position, and a trip device operable upon the occurrence of predetermined 60 conditions to cause said actuating means to automatically move said contact means to the open-circuit position, irrespective of the position of said operating member, said actuating means including two pairs of toggle links, one of the said 65 two pairs of toggle links being substantially straight when said interrupter is in the open-circuit position to facilitate rapid closing of the contact means during the circuit-closing operation, the other of the said two pairs of toggle links serving as a support for the first pair of toggle links in order to permit normal operation of said interrupter in response to movement of said operating member, said second pair of toggle links being normally restrained in a position where it 70 75

supports said first pair of toggle links in an operative position by means associated with said trip device.

6. In a circuit interrupter, separable contact means for opening and for closing the circuit, actuating means including an operating member for moving said contact members to the open and to the closed-circuit position, means biasing said contact means to the open-circuit position when 10 said interrupter is in the closed-circuit position, and a trip device operable upon the occurrence of a predetermined condition to cause said contact means to be moved to the open-circuit position by said biasing means, said actuating means including a pair of toggle links disposed intermediate said operating member and said contact means, said pair of toggle links being substantially straight when said interrupter is in the 15 open-circuit position to facilitate rapid closing 20 of said contact means during the circuit-closing operation, and support means for said pair of toggle links comprising a second pair of toggle links, said first pair of toggle links being bent at the knee when said interrupter is in the closed- 25 circuit position and said second pair of toggle links being substantially straight when said interrupter is in the closed-circuit position.

7. In a circuit interrupter, separable contact means for opening and for closing the circuit, 30 actuating means for moving said contact means to the open and to the closed-circuit position including a toggle linkage and an operating member, and an electro-responsive support means for normally holding said toggle linkage in an operative 35 position, said support means becoming incapable of holding said toggle linkage in the closed-circuit position upon the occurrence of predetermined conditions and thereby causing said actuating means to move said contact means 40 to the open-circuit position, said toggle linkage being operatively connected to said operating member through a slot and pin connection with the slot extending generally perpendicularly to the direction of movement of the operating member.

8. In a circuit interrupter, separable contact means for opening and for closing the circuit, 45 actuating means for moving said contact means to the open and to the closed-circuit position including a toggle linkage and a manually operable handle having a slot extending generally perpendicularly to its direction of movement, and an electro-responsive support means for normally holding said toggle linkage in an operative position, said support means becoming incapable 50 of holding said toggle linkage in the closed-circuit position upon the occurrence of predetermined conditions and thereby causing said actuating means to move said contact means to the open-circuit position, said toggle linkage being operatively connected to said operating handle through a pin in said slot in order that the 55 operation of said electro-responsive support means shall cause said actuating means to move said contact means to the open-circuit position irrespective of the position of said operating handle.

9. In a circuit interrupter, a pair of separable contact means for opening and for closing the circuit, actuating means for moving said contact means to the open and to the closed-circuit position, and a trip device operable to cause said actuating means to automatically move said contact means from the closed-circuit to the open-circuit position, said trip device including a single 70 trip bar movable to cause the operation of said 75

device, and two separate electromagnetic means, each individually responsive to different predetermined electrical conditions in the circuit controlled by said interrupter, for moving said trip bar and thereby effecting the operation of said trip device, one of said electromagnetic means including a movable armature entirely supported upon said trip bar, the other of said electromagnetic means including means movable to engage said trip bar to cause the operation of said trip device.

10. In a circuit interrupter, a pair of separable contact means for opening and for closing the circuit, actuating means for moving said contact means to the open and to the closed-circuit position, and a trip device operable to cause said actuating means to automatically move said contact means from the closed circuit to the open circuit position, said trip device including a single trip bar movable to cause the operation of said device, an armature entirely supported upon said trip bar, means responsive to the circuit controlled by said pair of separable contacts for attracting said armature upon the occurrence of predetermined conditions and thereby causing the operation of said trip device, and a second means likewise responsive to the circuit controlled by said pair of separable contacts for moving said trip bar to cause the operation of said trip device upon the occurrence of other predetermined conditions.

11. In a circuit interrupter, a pair of separable contact means for opening and for closing the circuit, actuating means for moving said contact means to the open and to the closed-circuit position, and a trip device operable to cause said actuating means to automatically move said contact means from the closed-circuit to the open circuit position, said trip device including a single trip bar movable to cause the operation of said device, an armature entirely supported upon said trip bar, means for attracting said armature upon the occurrence of predetermined conditions in the circuit controlled by said interrupter to cause the operation of said trip device, and means for causing the operation of said trip device upon the occurrence of other predetermined conditions in the circuit controlled in said interrupter, said means including a means of bimetallic material having a portion thereof that is movable to cause movement of said trip bar.

12. In a circuit interrupter, a pair of separable contact means for opening and for closing the circuit, actuating means for moving said contact means to the open and to the closed-circuit position, and a trip device operable to cause said actuating means to automatically move said contact means from the closed-circuit to the open-circuit position, said trip device including a single, pivotally mounted trip bar that is movable to cause the operation of said trip device, an armature entirely supported upon said trip bar, means for attracting said armature upon the occurrence of predetermined conditions in the circuit controlled by said pair of separable contacts, to cause the actuation of said trip device, and means for causing the operation of said trip devices upon the occurrence of other predetermined conditions in the circuit controlled by said pair of separable contacts, said means including a current-carrying means of bimetallic material having a portion thereof that is movable to cause movement of said trip bar.

13. In a circuit interrupter, a pair of separable contact means for opening and for closing the

- circuit, actuating means for moving said contact means to the open and to the closed circuit position, and a trip device operable to cause said actuating means to automatically move said contact means from the closed circuit to the open circuit position, said trip device including a single, pivotally-mounted trip bar of insulating material that is movable to cause the operation of said trip device, an armature entirely supported upon said trip bar, means for attracting said armature upon the occurrence of predetermined conditions in the circuit controlled by said pair of separable contacts to cause the actuation of said trip device, and means for causing the operation of said trip device upon the occurrence of other predetermined conditions in the circuit controlled by said pair of separable contacts, said means comprising a substantially U-shaped current carrying member of bimetallic material having a portion projecting outwardly from the closed end of said U, said portion being movable and being adapted to directly engage said trip bar to cause the operation of said trip device.
14. In a trip device for a circuit interrupter, a single trip bar movable to cause the actuation of said device, an armature entirely supported upon said trip bar, means for attracting said armature upon the occurrence of predetermined electrical conditions to cause the actuation of said device, and an electro-responsive means including means operable upon the occurrence of other predetermined electrical conditions to cause said trip bar to be moved to a position where it effects the actuation of said trip device.
15. In a multi-pole circuit interrupter, a plurality of pairs of separable contact means for defining a plurality of poles, actuating means for moving said contact means to open and to close the circuits controlled by said plurality of poles, and a trip device operable to cause said actuating means to automatically move a plurality of said contact means to the open circuit position, said trip device including a single trip bar extending across a plurality of the poles of said interrupter, a plurality of armatures entirely supported upon said trip bar, a plurality of means, each of which is energized in response to the circuit controlled by one of said pairs of contacts, for attracting each of said armatures individually to cause the actuation of said trip device upon the occurrence of predetermined electrical conditions, and means responsive to different predetermined conditions for moving said single trip bar to cause the actuation of said trip device.
16. In a multi-pole circuit interrupter, a plurality of pairs of separable contact means for defining a plurality of poles, actuating means for moving said contact means to open and to close the circuits controlled by said plurality of poles, and a trip device operable to cause said actuating means to automatically move a plurality of said contact means to the open circuit position, said trip device including a single trip bar extending across a plurality of the poles of said interrupter, a plurality of armatures entirely supported upon said trip bar, a plurality of means, each of which is energized in response to the circuit controlled by one of said pairs of contacts, for attracting each of said armatures individually to cause the actuation of said trip device upon the occurrence of predetermined electrical conditions, and a plurality of responsive tripping elements each energized in response to the circuit controlled by one of said pairs of contacts, each of said thermally responsive tripping elements including means movable upon the occurrence of predetermined conditions in the controlled circuit to directly engage said trip bar and thereby effect the actuation of said trip device.
17. In a multi-pole circuit interrupter, a plurality of pairs of separable contact means for defining a plurality of poles, actuating means for moving said contact means to open and to close the circuits controlled by said plurality of poles, and a trip device operable to cause said actuating means to automatically move a plurality of said contact means to the open circuit position, said trip device including a single trip bar movable to cause the actuation of said device, a plurality of armatures entirely supported upon said trip bar, a plurality of means, each of which is energized in response to the circuit controlled by one of said pairs of contacts, for attracting each of said armatures individually to cause the actuation of said trip device upon the occurrence of predetermined conditions, and means operable in response to different predetermined conditions to cause said trip bar to be moved to a position where it effects the actuation of said device.
18. In a multi-pole circuit interrupter, a plurality of pairs of separable contact means for defining a plurality of poles, actuating means for moving said contact means to open and to close the circuits controlled by said plurality of poles, and a trip device operable to cause said actuating means to automatically move a plurality of said contact means to the open circuit position, said trip device including a single, pivotally supported, trip bar which extends across a plurality of the poles of said interrupter and which is movable from a normal inoperative position to an operative position to effect the actuation of said trip device, a plurality of armatures supported on said trip bar at spaced intervals, a plurality of means, each of which is energized in response to the circuit controlled by one of said pairs of contacts, for attracting each of said armatures individually to cause the actuation of said trip device upon the occurrence of predetermined electrical conditions, and means operable in response to different predetermined electrical conditions to cause said trip bar to be moved from said normal inoperative position to said operative position.
19. In a circuit interrupter comprising a pair of separable contact members, actuating means for normally moving said members to the open and to the closed circuit position, and a trip device operable to cause said actuating means to automatically move said contact members from the closed circuit to the open-circuit position, said trip device including a trip member movable upon the occurrence of an overload from a normal inoperative position to an operative position to effect the actuation of said device, the combination of means adapted to detect break-down of insulation in the circuit controlled by the interrupter comprising an electro-responsive device operable to cause said trip member to be moved from said inoperative to said operative position, and a switching device movable from a normal open circuit position to a closed circuit position to effect the energization of said electro-responsive device.
20. In a circuit interrupter comprising a pair of separable contact members, actuating means for normally moving said members to the open and to the closed circuit position, and a trip device operable to cause said actuating means to automatically move said contact members from the

- closed circuit to the open-circuit position, said trip device including a trip bar movable upon the occurrence of an overload from a normal inoperative position to an operative position to effect the actuation of said device, the combination of means adapted to detect break-down of insulation in the circuit controlled by the interrupter comprising an armature movable to cause said trip bar to be moved from said inoperative 5 to said operative position, a coil means for attracting said armature, and a test switch movable from a normal open circuit position to a closed circuit position to effect the energization of said coil means.
- 15 21. In a multi-pole circuit interrupter, a plurality of pairs of separable contacts for defining a plurality of poles, actuating means for moving said contact means to open and to close the circuits controlled by said plurality of poles, and a trip device operable to cause said actuating means to move a plurality of said pairs of separable contacts to the open circuit position, said trip device including a trip bar movable from a normal inoperative to an operative position to effect 20 the actuation of said device, electro-responsive means operable when energized to cause said trip bar to be moved from said inoperative to said operative position, switching means movable successively from a normal open circuit position to a plurality of closed circuit positions to effect the energization of said electro-responsive means, said switching means being operable when moved to said closed circuit positions to connect said coil means successively into the circuit controlled by 25 each of a plurality of the poles of said interrupter.
- 30 22. In a multi-pole circuit interrupter, a plurality of pairs of separable contacts for defining a plurality of poles, actuating means for moving said contact means to open and to close the circuits controlled by said plurality of poles, and a trip device operable to cause said actuating means to move a plurality of said pairs of separable contacts to the open circuit position, said trip device including a trip bar movable from a normal inoperative to an operative position to effect 35 the actuation of said device, current-carrying, electro-responsive means operable to cause said trip bar to be moved from said inoperative to said operative position, and a test switch movable from a normal open circuit position to a plurality of separate closed circuit positions, the circuit controlled by each of a plurality of the poles of said interrupter being grounded through said current-carrying, electro-responsive 40 means when said test switch is moved to said closed circuit positions.
- 45 23. In a multi-pole circuit interrupter, a plurality of pairs of separable contacts for defining a plurality of poles, actuating means for moving said contact means to open and to close the circuits controlled by said plurality of poles, and a trip device operable to cause said actuating means to move a plurality of said pairs of separable contacts to the open circuit position, said trip device including a trip bar movable from a normal inoperative position to an operative position to effect the actuation of said device, an armature movable to cause said trip bar to be moved from said inoperative to said operative 50 position, a coil means for attracting said armature, a test switch movable successively from a normal open circuit position to a plurality of separate closed circuit positions, the circuit controlled by each of a plurality of the poles of said interrupter being grounded through said energizing coil when said switch is moved to said closed circuit positions, and means for limiting the current which shall flow through said coil when said test switch is in any one of said closed circuit positions.
- 55 24. In a circuit interrupter, a pair of separable contact means for opening and for closing the circuit, actuating means for moving said contact means to the open and to the closed-circuit position including a trigger biased to move and cause said contact means to move to open-circuit position, and a trip device operable to cause said trigger of said actuating means to automatically move said contact means from the closed circuit to the open circuit position, said trip device including a single trip bar having a latch portion normally holding said trigger and movable to cause the release thereof, an armature entirely supported upon said trip bar, means responsive to the circuit controlled by said pair of separable contacts for attracting said armature upon the occurrence of predetermined conditions and thereby causing the operation of said trip device, and a thermally responsive means likewise responsive to the circuit controlled by said pair of separable contacts for moving said trip bar to 60
- 65 70 75

cause the operation of said trip device upon the occurrence of other predetermined conditions.

27. In a trip device for a circuit interrupter having a trigger biased to move and cause opening of the circuit, a single trip bar having a latch portion thereon for holding said trigger and movable to cause the release of said trigger, an armature entirely supported upon said trip bar, means for attracting said armature upon the occurrence of predetermined electrical conditions to cause the actuation of said device, and thermally responsive means operable upon the occurrence of other predetermined electrical conditions to cause said trip bar to be moved to a position where it effects the actuation of said trip device.

28. In a circuit interrupter, separable contact means for opening and for closing the circuit, actuating means for moving said contact means to the open and to the closed-circuit position including an operating member and a link connected thereto by a slot and pin connection with the slot extending generally transversely of the direction of movement of the operating member, electro-responsive means normally limiting relative movement between said pin and slot so that movement of said operating member causes said link to move the contact means, and said electro-responsive means being operable to permit movement between said pin and slot so that said contact means may move to open the circuit without a corresponding movement of the operating member.

29. In a circuit interrupter, separable contact means for opening and for closing the circuit, actuating means for moving said contact means to the open and to the closed-circuit position including an operating member mounted for reciprocating movement and an actuated member connected to the operating member through a guide surface extending generally transversely of the direction of the reciprocating movement of the operating member, electro-responsive means normally limiting relative movement between said operating member and said actuated member so that movement of said operating member in one direction causes said actuated member to move the contact means to close the circuit, said electro-responsive means being operable upon the occurrence of a predetermined condition to permit said actuating member to slide along said guide surface and cause movement of said contact means to open the circuit without movement of said operating member, and means for causing movement of said operating member in the opposite direction after movement of said contact means to open the circuit in response to operation of said electro-responsive means.

30. In a circuit interrupter, separable contact means for opening and for closing the circuit, actuating means for moving said contact means to the open and to the closed-circuit position including an operating member mounted for reciprocating movement and an actuated member connected to the operating member through a guide surface extending generally transversely of the direction of the reciprocating movement of the operating member, holding means normally limiting relative movement between said operating member and said actuated member so that movement of said operating member in one direction causes said actuated member to move the contact means to close the circuit, electro-responsive means for releasing said holding means to permit said actuated member to slide along

said guide surface and cause movement of said contact means to open the circuit without requiring movement of said operating member, and means for thereafter causing movement of said operating member to open circuit position and for automatically resetting said holding means.

31. In a circuit interrupter, separable contact means for opening and for closing the circuit, actuating means for moving said contact means to the open and to the closed-circuit position including an operating member mounted for reciprocating movement and an actuated member connected to the operating member through a guide surface extending generally transversely of the direction of the reciprocating movement of the operating member, holding means normally limiting relative movement between said operating member and said actuated member so that movement of said operating member in one direction causes said actuated member to move the contact means to close the circuit, electro-responsive means for releasing said holding means to permit said actuated member to slide along said guide surface and cause movement of said contact means to open the circuit without requiring movement of said operating member, a manually operable member for releasing said holding means independently of said electro-responsive means, and means for thereafter causing movement of said operating member to open circuit position and for automatically resetting said holding means so that said contact means may be reclosed by movement of the first said operating member.

32. In a multi-pole circuit interrupter, a plurality of pairs of separable contact means for defining a plurality of poles, actuating means for moving said contact means to open and to close the circuits controlled by said plurality of poles and including a trigger biased to move and cause said contact means to move to open-circuit position, and a trip device operable to cause said trigger of said actuating means to automatically move a plurality of said contact means to the open circuit position, said trip device including a single trip bar having a latch portion normally holding said trigger and movable to cause the release thereof, a plurality of armatures entirely supported upon said trip bar, a plurality of means, each of which is energized in response to the circuit controlled by one of said pairs of contacts, for attracting each of said armatures individually to cause the actuation of said trip device and the release of said trigger upon the occurrence of predetermined conditions, and means operable in response to different predetermined conditions to cause said trip bar to be moved to a position where it effects the actuation of said device and the release of said trigger.

33. In a multi-pole circuit interrupter, a plurality of pairs of separable contact means for defining a plurality of poles, actuating means for moving said contact means to open and to close the circuits controlled by said plurality of poles and including a trigger biased to move and cause said contact means to move to open-circuit position, a trip device operable to cause said trigger of said actuating means to automatically move a plurality of said contact means to the open circuit position, said trip device including a single trip bar having a latch portion normally holding said trigger and movable to cause the release thereof, said actuating means including a handle member normally movable for opening and closing all of said contact means, a plurality

of armatures entirely supported upon said trip bar, a plurality of means, each of which is energized in response to the circuit controlled by one of said pairs of contacts, for attracting each of said armatures individually to cause the actuation of said trip device and the release of said trigger upon the occurrence of predetermined conditions, means operable in response to different predetermined conditions to cause said trip bar to be moved to a position where it effects the actuation of said device and the release of said trigger, and said release of said trigger causing opening of said contact means by said actuating means irrespective of the position in which said handle member may be held.

34. In a multi-pole circuit interrupter, a plurality of pairs of separable contact means for defining a plurality of poles, actuating means for moving said contact means to open and to close the circuits controlled by said plurality of poles and including a trigger biased to move and cause said contact means to move to open-circuit position, a trip device operable to cause said trigger of said actuating means to automatically move a plurality of said contact means to the open circuit position, said trip device including a single

trip bar having a latch portion normally holding said trigger and movable to cause the release thereof, said actuating means including a handle member normally movable for opening and closing all of said contact means without causing release of said trigger by said latch portion, a plurality of armatures entirely supported upon said trip bar, a plurality of means, each of which is energized in response to the circuit controlled by one of said pairs of contacts, for attracting each of said armatures individually to cause the actuation of said trip device and the release of said trigger upon the occurrence of predetermined conditions, means operable in response to different predetermined conditions to cause said trip bar to be moved to a position where it effects the actuation of said device and the release of said trigger, said release of said trigger causing opening of said contact means by said actuating means irrespective of the position in which said handle member may be held, and said handle member being operable to return said trigger into engagement with said latch portion after opening of said contact means.

KURT WULSTEN. 25
